LINGERIE PACKAGE OR THE LIKE

Maurice Perelman, 10 San Francisco, Naucalpan de Juarez, Mexico

Filed Feb. 14, 1972, Ser. No. 226,356

Term of patent 14 years

Int. Cl. D9—03

U.S. Cl. D9—193

Fig. 1.

Fig. 3.

Fig. 2.

FIG. 1 is a top perspective view of a lingerie package or the like embodying my new design, the side opposite that shown being substantially the same in appearance as the side shown except for the omission of the figure 8 design;

FIG. 2 is a bottom plan view; and

FIG. 3 is a reduced scale vertical sectional view taken through the center and with the contents omitted for convenience of illustration.

I claim:

The ornamental design for a lingerie package or the like, substantially as shown and described.
